UNITED STATES PATENT OFFICE

ROGER B. WHITMAN, OF NEW HYDE PARK, NEW YORK

GASOLINE PUMP

Application filed March 5, 1931. Serial No. 520,288.

Important objects of the present invention are, to provide a novel gasoline pump with a casing in the form of an elephant having a flexible proboscis through which the gasoline 5 is conducted from the pump, the proboscis being capable of swinging in any direction for convenient discharge of the gasoline into an automobile tank or other receptacle; to provide such a pump casing designed for 10 fitting over a pump of standard form; to provide such a casing designed to permit convenient operation of the pump from the exterior of the casing and to render the pump discharge meter easily readable; to provide 15 a combination of such a casing with a pump together with a discharge hose leading from the outlet of the enclosed pump outward through the proboscis; to provide such a combination wherein the discharge hose is 20 extensible and retractible through the proboscis; to provide for automatic retraction of the discharge hose inward through the proboscis when the hose nozzle is released; to provide 25 the proboscis with a resilient structure permitting free flexure in all directions and capable of maintaining its shape and returning it to a normal, non-obstructing position when released; and to provide the casing with other desirable features of design 30 which will appear hereinafter.

In the drawing, Fig. 1 is a side elevation of the pump and casing mounted in operative position;

Fig. 2 is a front view of the casing partly in section;

Fig. 3 an enlarged section taken on the line 3—3 of Fig. 2; and

Fig. 4 a vertical transverse section taken 40 through the top of the casing showing the latter modified for a different location of the dials of the pump meter.

The casing designated 1, is shown as mounted over an upright gasoline pump P of a standard form customarily employed at 45 gasoline filling stations. The casing is in the form of a seated elephant, and comprises a hollow, rigid main section 2 forming the body, limbs and head of the elephant and a flexible tubular hose concealing and projecting section 3 in the form of a trunk or pro-

boscis. In the present instance the pump is shown as mounted upon a flat curbing C separating two driveways, and the figure of the elephant is made rather narrow to avoid overhang from the curbing. The seated posture 55 of the elephant best accommodates the upright pump.

At its under side the casing has an opening 4 for fitting it over the pump and said opening is surrounded by a flat flange 5 which 60 seats upon the curbing or other support and is bolted or otherwise secured. At the back of the elephant the casing is provided with a door 6 of material size hinged to the casing, as at 7, and affording access to the pump and 65 other parts, to be described hereinafter. In the present instance the door is formed and marked to simulate a blanket upon the back of the elephant. The form and location of the door may be varied however. 70

A gasoline pump of the type shown is provided with a meter having two dials located at opposite sides of the pump near the top thereof, and indicating hands cooperating with said dials to indicate the volume of gasoline 75 discharged from the pump. In the form of the invention shown in Figs. 1, 2 and 3 of the drawing, the meter dials 8 are carried by the casing section 2 and are mounted at opposite sides of the elephant's head, the 80 meter shaft 9 being extended to reach the dials and bearing the indicating hands 10. The pump also has a manual operating crank 11 and one side of the casing section 2 has an aperture through which the crank shaft 85 12 extends, the crank being conveniently mounted upon the shaft, outside of the casing.

The hose concealing and protecting section 3 comprises a tapering, tubular section 13 90 of rubber or other suitable flexible, and preferably resilient and water-proof material. At its upper end said section is fitted around an annular flange 14 formed upon the head portion of casing section 2, and is secured in any suitable manner. Said flange 14 defines an aperture through which the tubular section communicates with the interior of the casing body. The union between the said 95 section and the body of the casing may be 100

varied however. Fitted within tubular section 13 is a tapering spiral spring 15 which maintains the shape of the trunk and gives it a desired resilience. In the present instance this spring extends throughout the entire length of section 13 but in some cases a shorter spring may be sufficient. A rigid sleeve or ferrule 16 is bound to the outer end of the tubular section and forms a guide for 10 the pump discharge hose 17.

Within the top portion of the casing are two pulleys 18 for training the hose 17. In the present instance these pulleys are supported by a bracket 19 mounted upon the 15 pump. They may, however, be supported by the casing section and, if desired, other suitable means may be employed for training the hose. The hose is shown as an extensible one normally having a considerable length of 20 slack within the casing and operatively engaged by a retracting pulley 20. Pulley 20 is supported by an arm 21 pivoted to the casing as at 22. The hose is connected to the pump outlet 23, trained downward around the pulley 20, upward over pulleys 18 and outward through the length of the tubular trunk and the ferrule 16 through which it is freely 25 slideable. Attached to the outer end of the hose is a nozzle 24 having a stop flange 25 to abut 30 the ferrule 16 and limit the retraction of the hose. The hose is retracted by the weight of the pulley 20 and its supporting arm. In some cases the reach of the flexible trunk may 35 be considered sufficient and the extensible hose feature may be omitted.

In filling the tank of an automobile or other receptacle with gasoline the nozzle 24, or the trunk, is grasped and the latter is flexed in any direction necessary for the nozzle to 40 reach the receptacle. If the reach of the trunk is insufficient, the hose is pulled out through the trunk to the required extent. Preferably the nozzle has a hook-like projection 26 for anchoring in the filling opening 45 of the receptacle to hold the nozzle in place and the hose extended. Having so connected the nozzle, the pump handle or crank 11 is operated and the meter dials are read from either side of the casing. At the conclusion 50 of the filling operation the nozzle is detached from the receptacle and the hose-retracting means is permitted to draw the hose inward through the trunk until the nozzle stop 55 abuts the ferrule 16. Then, upon release of the trunk, the spring 15 will swing it into normal, pendant position, where it is out of the way. The flexible, tubular section in the 60 form of a trunk forms a protecting and concealing means for the length of gasoline hose which is usually free and ordinarily is exposed at the side of the pump. The tubular section is large at its upper end and tapers toward the ferrule 16 at its outer end. This permits the trunk to be swung in any direction and moved about freely in use without 65

binding the hose on the interior of the section. The interior arrangement of the spring protects it and at the same time provides a means for returning the tubular section or trunk to its normal position with respect to the casing; and because of its flexible construction the normal position of the tubular section may be varied in order to adapt the device for the desired use and to suit the desired position of the pump. 75

It will be seen that I have provided a gasoline pump apparatus which is interesting and ornamental and capable of convenient operation. While I have shown and described a satisfactory form of my invention, I do not wish to be limited strictly to this disclosure but reserve the right to make such changes as will lie within the scope of the claims. Also, while I have shown and described the invention in connection with a 80 gasoline pump, it is capable of advantageous use in connection with other fluid dispensing means. 85

In Fig. 4 is shown a modification of the invention wherein the meter dials 8a are directly carried by the pump in the usual manner, and the casing section 2 has observation apertures 27 in its opposite sides and registering with the dials. These apertures may have transparent panels or lenses 28. 90

What I claim is:

1. A gasoline pump comprising a measuring pump and a casing surrounding and enclosing said measuring pump, the top portion of the casing extending above the top of the measuring pump and provided with a downwardly and forwardly projecting opening; a hollow, conically shaped, flexible member secured to the casing over said opening and provided with an opening at its lower end; a 100 hose from the measuring pump adapted to extend through the flexible member and said open end and provided with a nozzle; and means for preventing the nozzle from being drawn through said end opening into the 105 flexible member. 110

2. A gasoline pump comprising a measuring pump entirely enclosed in a casing, a portion of the casing provided with a downwardly and forwardly extending opening 115 central of the front of the casing, a flexible conical hose concealing and protecting member secured to the casing over said opening, said member comprising a conically coiled spring covered with flexible water-proof material, a ferrule secured to and providing an open end at the lower end of said flexible member, a nozzle supported by said ferrule, and a hose within the casing and extending through the flexible member from the measuring pump to said nozzle. 120

3. The gasoline pump as in claim 2, where- 125 in said hose is longer than the flexible mem- ber and may be drawn out through said fer- rule opening, and means within the casing 130

for retracting said hose and normally maintaining the nozzle in contact with said ferrule.

4. A gasoline pump comprising a measuring pump entirely enclosed in a casing; a downwardly and forwardly directing portion at the top of the casing and having an opening at its lower end and in the front of said casing, a flexible member forming an extension of said downwardly and forwardly directed portion of the casing and secured thereto over said opening, a retractible hose extending from the measuring pump through said flexible member and provided with a nozzle, a ferrule surrounding an opening at the lower end of the flexible member through which the hose may be drawn, pulleys mounted within the casing and adapted to direct said hose to the center of the casing and through said flexible member, and means within the casing cooperating with said pulleys for retracting said hose.

5. A gasoline pump comprising a measuring pump enclosed in a casing; said casing being provided at its upper forward portion with an extension with an opening at the front, a flexible conically shaped member secured to the extension portion over said opening, said flexible member being provided with an opening surrounded by an annular ferrule at its lower end, a hose of greater length than the length of the flexible member connected at the upper end of the pump and extending through said member and the ferrule, said hose being provided with a nozzle having means to engage the ferrule to prevent retracting the nozzle into the flexible member, pulleys within the head of the casing above said pump for directing the hose to the front central portion of the casing and through said flexible member, a hose-retracting floating pulley riding in a loop of the hose, and means for supporting said floating pulley within the casing for vertical motion therein at the rear of the pump as the hose is drawn out and retracted over said directing pulleys.

6. The gasoline pump as in claim 5, wherein in the measuring pump is provided with a dial and the surrounding casing is spaced from the measuring pump and provided with an opening registering with the said dial.

7. A gasoline pump comprising a measuring pump, a casing surrounding and enclosing said pump, the upper portion of the casing being provided with a downwardly and forwardly projecting portion having an opening at its lower end; a hollow, conical, downwardly tapered hose protecting and concealing member secured to the lower end of the said casing extension and provided with an opening at its lower end; means to render said hollow member flexible and resilient and to hold it in its normal hose holding position and permitting it to be flexed in any

direction for use; a hose connected to the measuring pump and extended through the said flexible member and provided with a nozzle; and means for preventing the nozzle from being drawn through the end opening into the flexible member.

8. A gasoline pump as claimed in claim 7, wherein said hose is longer than the hollow, flexible member and may be drawn out through the said ferrule opening, and means within the casing for yieldingly retracting the said hose and normally maintaining the nozzle in contact with said ferrule.

In testimony whereof I hereunto affix my signature.
